UNITED STATES PATENT OFFICE

2,427,188

DEVICE FOR DRAINING UMBRELLAS

Anna Bossart, Zurich-Hoengg, Switzerland

Application June 28, 1945, Serial No. 602,011
In Switzerland November 20, 1944

7 Claims. (Cl. 135—48)

1

The object of the present invention is to avoid the dripping of water from a closed umbrella by the provision of a watertight container which can be easily attached to the umbrella by means of a suitable holding device and can be easily detached after use.

The holding device may for instance, consist of a flap in the shape of a semi-cylindrical member which is pivotally mounted upon the container so that in the open position of the flap the end portion or point of the umbrella can be readily inserted into the container, whilst in the closed position of the flap the container is firmly clamped to the umbrella.

In order to improve or ensure the firm connection between the container and the umbrella, the flap and the corresponding semi-cylindrical portion of the container may advantageously be internally padded with a resilient mass for instance, spongy rubber.

A tension device preferably consisting of a rubber cord may be provided in such a manner that it tends to hold the flap both in the closed and in the open position. A handle or finger-piece may be provided upon the flap to facilitate manipulation.

Two constructional forms of the invention are shown in the accompanying drawings by way of example.

Figs. 1 to 4 show the first construction, Fig. 1 being a sectional elevation of the complete draining device in its operative position and with the umbrella end or point inserted into the device.

Fig. 2 is an elevation at right angles to the sectional elevation of Fig. 1 with the flap in the closed position.

Fig. 3 is an elevation corresponding to Fig. 2 but showing the flap in the open position.

Fig. 4 is a top view of the container corresponding to Fig. 1.

Figs. 5 to 7 show the second construction, Fig. 5 being a sectional elevation and Figs. 6 and 7 showing a resilient holding device in elevation and top view.

Referring now to Figs. 1 to 4, 1 indicates a waterproof container. This may be made of various materials for instance, artificial moulding material, plastic, stiff waxed fabric, papier-mâché, thin aluminium, or hard rubber. The lower part of the container may be made of waterproof fabric for instance, oiled silk, impregnated cotton, or the like. The rain-water which has accumulated in the container is indicated by the numeral 2 and the inserted end of 55

2

the umbrella by the numeral 3. Preferably different models should be used for gentlemen's and ladies' umbrellas. The upper part of the container shown in Figs. 1 to 4 consists of a portion 1a permanently attached to the container which is of semi-cylindrical shape, and the semi-cylindrical flap 1b. The flap 1b is pivotally mounted upon the container 1 at 1c by a hinge. Both the portion 1a and the flap 1b are internally padded with a resilient mass 4 the object of which is to absorb water running down from the fabric of the umbrella and transfer said water to the container, also to improve the connection between the container and the umbrella. 15 The resilient mass may preferably consist of spongy rubber or similar material.

The flap 1b is provided with a handle or finger-piece 5 to facilitate its manipulation. Rubber pulls 6 provided on both sides of the container 20 serve to hold the flap both in the closed and in the open position.

Instead of rubber pulls 6, other devices might be used, for instance, an elastic band might be provided and the upper part of the container 25 might also be somewhat resilient to enable the end of the umbrella to be inserted into the resilient upper part which is then firmly held upon the umbrella by the resilient band.

Instead of a flap various other holding devices 30 might be used, for instance, a clamping device might be provided inside the container which whilst allowing of the end of the umbrella to be inserted into the container, will firmly hold the inserted umbrella end. Such a device is for 35 instance, shown in Figs. 5 to 7 and consists of a ring formed with springs 7. This ring is inserted into the top part of the container 1 and is held therein by projections 8 formed on the inside of the container. In this construction 40 the container may be provided at the top with a ring 9 made of water absorbing material for instance, spongy rubber, and held by projections 10 formed in the container.

I claim:

45 1. A draining device for umbrellas comprising in combination: a watertight container and means for detachably attaching said watertight container to the end of an umbrella, said means comprising a semi-cylindrical top portion of the container and a corresponding semi-cylindrical flap pivotally mounted on said container, said top portion of the container and said flap in its closed position being adapted to grip the end of the umbrella.

2. A draining device for umbrellas comprising

in combination: a waterproof container having a semi-cylindrical top portion; a semi-cylindrical flap pivotally mounted on said container and adapted in its closed position to grip together with said top portion of the container the end of the umbrella and means for holding said flap both in the closing and in the open position.

3. A draining device for umbrellas comprising in combination: a waterproof container having a semi-cylindrical top portion; a semi-cylindrical flap pivotally mounted on said container and adapted in its closed position to grip together with said top portion of the container the end of the umbrella and means for holding said flap both in the closing and in the open position said means consisting of a resilient pull device fixed at one end to the container and at the other end to the flap.

4. A draining device for umbrellas comprising in combination: a watertight container having a semi-cylindrical top portion; a semi-cylindrical flap pivotally mounted on said container and adapted together with the semi-cylindrical top portion of said container to grip the end of the umbrella; said semi-cylindrical top portion of the container and said semi-cylindrical flap being padded with a resilient water absorbing material.

5. A draining device for umbrellas comprising in combination: a watertight container having a semi-cylindrical top portion; a semi-cylindrical flap pivotally mounted on said container and adapted in its closing position to grip in conjunction with the semi-cylindrical top of the container the end of an umbrella; and two rubber cords fixed to said flap and said container and

adapted to hold said flap both in its open and in its closed position.

6. A draining device for umbrellas comprising in combination: a watertight container having a semi-cylindrical top portion; a semi-cylindrical flap pivotally mounted on said container and adapted in its closing position to grip in conjunction with the semi-cylindrical top of the container the end of an umbrella; and two rubber cords fixed to said flap and said container and adapted to hold said flap both in its open and in its closed position said semi-cylindrical top portion of the container and said flap being padded with a water absorbing material.

7. A draining device for umbrellas comprising in combination: a waterproof container having a top portion padded with water absorbing resilient material and adapted to grip the lower end of an umbrella, and spring means inside said waterproof container for clamping the tip of the umbrella.
